UNITED STATES PATENT OFFICE

EDWIN W. PIERSON, OF NEWARK, NEW JERSEY, ASSIGNOR TO MERGENTHALER LINOTYPE COMPANY, A CORPORATION OF NEW YORK

SLUG-CASTING MACHINE

Application filed February 7, 1929. Serial No. 338,131.

This invention relates to slug casting machines, such as linotype machines of the general organization represented in U. S. Letters Patent to O. Mergenthaler No. 436,532, wherein circulating matrices are assembled in line together with expanding spacers or spacebands, the composed line lifted up between a pair of fingers of a delivery slide and then transferred thereby horizontally into a so-called "first elevator", which thereupon descends to present the composed line in casting position between a pair of vice jaws. One of these jaws (usually the left-hand jaw) is adjustable toward and from the opposing or right-hand jaw to accommodate lines of different lengths. In the normal operation of the machine, the line transfer slide is stopped within the first elevator in a definite predetermined position so that when the composed line is lowered between the vice jaws, the matrix at the extreme right will be flush or nearly so with the clamping face of the right-hand jaw. A small space, however, usually occurs between the matrix at the opposite end of the line and the left-hand jaw on account of the slight variations in length of the lines as ordinarily composed, but this or any other space in the line is filled out by the expansion of the spacebands during justification. In practice, the justification of the composed lines is usually carried out in two stages, i. e. before and after the matrices are aligned against the mold, these justifying operations being effected by a vertically movable bar arranged to engage the spacebands at their lower ends. In the first stage, the justification bar operates in an inclined position with reference to the matrix line, while in the second stage, it operates in a horizontal position, so that in effecting the preliminary justification of the line the bar is caused to engage the spacebands successively from right to left as it drives them upwardly through the line, whereas in effecting the final justification of the line it is caused to engage the spacebands successively from left to right, since at that time the spacebands stand as the bar left them after the preceding operation. The preliminary justification thus

tends to adjust the line toward the left to fill out any spaces or looseness at that end of the line, while the final justification, in bringing all of the bands to a common level, tends to adjust the line toward the right to fill out any looseness in that direction as well as to equalize the spacing of the words throughout the line. The final justification, however, takes place while the line is held by the first elevator under spring tension against the mold, for "face alignment" and consequently, due to the frictional resistance offered by the matrices, this final justifying operation cannot always be relied upon to insure a perfectly tight "lock-up", and particularly in the case of lines ranging from 30 to 42 ems in length. In other words, for one reason or another, such as abnormal looseness at the extreme right occurring when a line is overthrown during its transfer to the first elevator, or the binding of one or more of the matrices or spacebands in their supporting guides, slight spaces or crevices are frequently left in the composed lines after final justification. These crevices will not only result in the casting of imperfect slugs, but if exaggerated, they are likely to cause "front squirts" and lead to serious damage to the parts and danger to the operator. Moreover, the force of the final justification is often spent against one or two spacebands at the extreme left of the line, causing them (especially the thinner ones) to buckle or break and thus giving rise to further annoyance, expense and loss of time in operating the machine.

The present invention is directed to a new scheme of justification which will not only overcome the objections above noted but which in addition will produce a more uniform and more nearly perfect spacing of the word groups of the line. Briefly stated, it is proposed to straighten up the justification bar during the first justifying stage and immediately after it completes its initial thrust in an inclined position, leaving it free to operate in the regular way during the second justifying stage. The justification bar is thus given two distinct impulses in the first justifying stage, one an upward move-

ment while in an inclined position to push the spacebands upward progressively from right to left as heretofore, and the other a straightening up motion (a swinging movement of the bar from its inclined position to a horizontal position while raised) to even up the spacebands at their lower ends by lifting upwardly thereon progressively from left to right. This second impulse of the justification bar, taking place as it does in the preliminary justification, is most advantageous, because at that time the matrix line is not engaged with the mold for alignment purposes and hence the matrices and spacebands composing the line have practically complete freedom of movement and can for that reason more readily respond to the expanding influence of the spacebands as they are driven up through the line by the justification bar, first progressively in one direction and then progressively in the opposite direction. As a result, any looseness in the line at any point, whether at the extreme right or the extreme left or in between, is taken up by the spacebands with reasonable certainty, thereby avoiding the objectionable crevices or spaces above referred to; and moreover, for the same reasons, any excess space in the composed line is evenly and uniformly distributed between the different word groups composing the line. In effecting the final justification of the line, the justification bar as above stated is operated in the usual way, being moved upwardly while in a horizontal position, but since these spacebands have already (in the preliminary justification of the line) been brought into common horizontal alignment at their lower ends, they are not acted upon successively from left to right as heretofore, but all of them are engaged by the bar at the same time, this final operation thus lending itself to the complete and uniform spacing of the line.

While various expedients might be resorted to for operating the justification bar in the manner above described, the present invention has been designed so that the standard parts of the commercial machines may be used with an almost trifling change, which is obviously a great advantage. The precise manner in which this is accomplished will best be understood from the detailed description to follow.

In the accompanying drawings, the invention has been shown merely in preferred form and by way of example, but obviously many changes and variations may be made therein and in its mode of operation, which will still be comprised within its spirit. It should, therefore, be understood that the invention is not limited to any specific form or embodiment except in so far as such limitations are specified in the claims.

Referring to the drawings:

Fig. 1 is a front view of a portion of a lino-

type machine embodying the present improvements, and showing the justifying mechanism as it appears just before the preliminary justification of the matrix line is effected;

70

Fig. 2 is a skeleton view, showing the justification bar and parts associated therewith in the relative positions they occupy when the initial stroke of the bar is completed;

75

Fig. 3 is a similar view showing by the full and dotted lines other positions of the parts in the course of their operation; and

80

Fig. 4 is a vertical fore-and-aft section through the vise frame and cam shaft with the justifying mechanism in the position shown in Fig. 2.

85

Referring to Fig. 1, the matrices X and spacebands Y, after being composed in line in the assembler A, are lifted up between the fingers B¹, B² of the delivery slide B, which transfers the line horizontally through the intermediate channel C to the position indicated by dotted lines, where it is arrested by the engagement of the slide against the fixed stop C¹. At the time of such transfer, the first elevator D is in position to receive the line, and then descends to present it at the casting level (as shown by the full lines in Fig. 1) in front of the mold E and between the clamping jaws F, F¹, the latter being mounted in a stationary portion G of the machine frame, commonly known as the "vise frame." The finger B¹ at the right is rigidly connected to the delivery slide proper, but its companion B² is usually free thereon so that it may serve, irrespective of variations in the length of the lines, to keep the matrices at the left from tilting or toppling over as the line is being transferred.

90

The left-hand jaw F is adjustable toward and from the relatively fixed right-hand jaw F¹ so as to vary the distance therebetween according to the length of the composed matrix line, and its adjustment is usually effected by means of an annularly grooved rod H arranged behind the jaw and which may be set to any given measure as desired. The rod H serves as an abutment for the jaw F and extends horizontally through the end bracket G¹ of the vise frame G in which it is slidably mounted. In order that the rod H may sustain the jaw F against the force of justification, it is locked in its adjusted positions to a block K, which is held resiliently by a spring or detent (not shown) in contact with a vertical reciprocatory wedge bar L supported facewise against the bracket G¹ and operable periodically during each machine cycle of operation. The bar L is formed near its lower end with a transverse slot L¹ and at its top with upper and lower wedge surfaces L², L³, the high points of which are adapted.

110

when the bar L is all of the way up or all of the way down, to locate the jaw F through the block K in its proper position. When, 115

120

125

130

however, the wedge bar stands about midway between these extreme positions, the low portions of the wedge surfaces L^2 , L^3 allow a slight recession of the block K and rod H away from the jaw F for reasons later to appear.

The operation of the wedge bar L is effected in one direction by a pull spring L^4 anchored to the bracket G¹, and in the opposite direction by a fore-and-aft rocking lever M, forked at the front and fulcrumed at the rear on a horizontal shaft N located below the cam shaft O. One member of the forked end of the lever M is connected to the wedge bar L by a cross pin m arranged in the slot L¹, and the other member m^1 of said forked end is located directly below a collar P secured to one of a pair of vertical slide rods P¹, P². These rods are mounted in the vise frame G and carry at their upper ends the justification bar P³ to which they are pivotally connected. The rod P² (see Fig. 1) is supported against the action of gravity by a second fore-and-aft lever M¹ also fulcrumed on the shaft N and whose free end engages a collar P⁴ secured to said rod. The rod P¹, on the other hand, is supported by the rod P² through a connecting link or strut P⁵, which extends obliquely upward from the collar P⁴ and loosely engages a pin p secured to the justification bar P³. The purpose of this loose connection between the bar and strut is to allow a slight movement of the rod P¹ relatively to the rod P² and thus to permit the justification bar to be moved from an inclined position to a horizontal position, or vice versa. Normally, the justification bar P³ is supported by the strut P⁵ and rod P⁴ in its inclined position as shown in Fig. 1 and will therefore remain in this position when raised by the lever M¹ to perform the preliminary justification of the line. The lever M¹ is also capable of moving the justification bar through the collar P and rod P¹, but acts only during the second or final justifying period, at which time both levers M and M¹ act together to lift the bar in a horizontal position against the spacebands.

The levers M, M¹ are actuated by powerful compression springs M², M³ seated in the base frame beneath the levers and individually controlled by a corresponding pair of cams O¹, O² formed generally with relatively low portions O³, O⁴, intervening high portions O⁵, and extended concentric portions O⁶. These cams (see Fig. 4) are keyed to the main shaft O and sustain the levers, through the medium of anti-friction rollers M⁴, M⁵, against the tension of their actuating springs. With this arrangement, and during each rotation of the shaft O, the rollers M⁴, M⁵ under the influence of the springs M², M³ are caused to follow the contour of the respective cams O¹, O², and allow the levers M, M¹ to be raised and lowered in definite synchronism for the

operation of the justification bar P³ in two distinct stages. The bar in the first stage of its operation is moved while in an inclined position toward and from the matrix line by the action of the spring M² under the control of the cam O², and in the second stage, it is moved through the same path while in a horizontal position by the action of both springs M², M³ under the joint control of the two cams O¹, O².

The different steps in the justification of a matrix line as ordinarily effected in the commercial linotype machines take place in the following order or sequence. Assume a composed line of matrices and spacebands to have reached the dotted line position shown in Fig. 1, where it has been stopped by the engagement of the delivery slide B against the fixed stop C¹. If the line is "full", the lower end of the delivery slide finger B² will have entered the recess f in the top of the left-hand jaw F (as indicated), but if it is "short" the finger will stand a corresponding distance to the right of such position, so that when the line, at the start of the cycle, is lowered between the vise jaws, the space will occur adjacent the clamping face of the left-hand jaw F, the finger B² always standing in perfect alignment with the right-hand jaw F¹. As soon as the line is positioned between the jaws, the mold E is advanced against the same preparatory to justification and the roller M⁴ of the fore-and-aft lever M is about to engage the low section O³ of the cam O¹, which as the cycle proceeds permits said lever to rise high enough to free the wedge bar L so that it may be drawn upwardly by its actuating spring L⁴ to the position shown in Fig. 2. At this time, the lever M stops short of the collar P, there being sufficient space allowed for such lost motion between said collar and the member m¹ (see Fig. 1). The low section O⁴ of the cam O² is then brought to bear upon the roller M⁵, which allows the justification bar to be lifted by the other lever M¹ into engagement with the spacebands Y to effect the preliminary justification of the line. By this action and due to the inclination of the bar, there is a tendency to adjust the line to the left and any space occurring adjacent the jaw F is closed up by the expansion of the spacebands. By a continued rotation of the cams O¹, O², both levers M, M¹, are lowered to the dotted line position indicated in Fig. 3, and the reduced portion of the wedge bar L is brought opposite or behind the block K, which thus allows the clamping action of the jaws to be temporarily relieved and leaves the line free to be pulled bodily upward by the elevator D against the lip of the mold in effecting the horizontal alignment of the matrix characters with the mold slot. This aligning operation is commonly referred to as "face alignment" and prepares the line for the final justification, which im-

mediately follows. The lever M, after allowing the wedge bar 5 to rise again to its former position, is now adapted to engage the collar P and straighten up the justification bar, which, while disposed in such horizontal position and as permitted by the low sections O⁴ of the two rotary cams, is forced upwardly against the spacebands by the action of both levers M, M¹ under the propelling influence of the springs M², M³. After the casting operation, the justification bar P³ and wedge bar L are returned to their normal position (Fig. 1), and the composed line is lifted by the elevator D from its position between the jaws for separation and distribution of the matrices and spacebands.

The foregoing parts, their construction and mode of operation, except as hereinafter pointed out, are or may be the same as those embodied in the commercial linotype machine and in themselves constitute no part of the present invention, which is devoted essentially to certain improvements whereby the justification bar during the first stage of its operation is shifted from its inclined position to a horizontal position parallel with the matrix line in effecting the preliminary justification thereof. This is accomplished, in the present instance, simply by forming the cam O¹ with a recess O⁷ located in the low portion O³ thereof, and by positioning the collar P on the vertical rod P¹ about one inch lower than heretofore. The latter change enables the fork member m¹ of the lever M to engage the collar P and raise the corresponding end of the justification bar P³ after the bar has been lifted by the lever M¹ and while the spring M² is still capable of exercising its greatest power.

As a result of these changes, simple as they are, after the justification bar has been raised during the first stage of its operation to the position shown in Figs. 2 and 4 in the manner before described, the recess O⁷ is brought into registry with the roller M⁴ and allows the lever M to rise under the influence of the spring M² into engagement with the collar P and, through the rod P¹, swing the bar from the position shown in Fig. 2 to that shown by the full lines in Fig. 3. In this way the line is subjected to endwise spreading in both directions and any looseness or spaces that may exist between the matrices eliminated. Moreover, all of the bands are driven up an equal distance through the line, which insures a uniform spacing of the words, and the line is left in perfect condition for the subsequent operations of "face alignment" and final justification, which are effected in the usual way and as above described. If desired, the right end of the justification bar may be lowered slightly before the opposite end is swung upwardly in order to facilitate the adjustment of the line toward the right, since the

bar as it is lifted by the lever M would then be better adapted to engage the spacebands successively from the left toward the right in bringing them to a common level. In this event, a slight rise or swell in the low section O⁴ of the cam O² is all that would be required. As the advantages of this new construction and operation of the parts were fully pointed out in the preamble, it is not believed any further elaboration here is necessary, altho it may again be pointed out that the characteristic feature of the invention resides in the straightening up of the justification bar in the first stage of justification as distinguished from the second stage.

Having thus described my invention, what I claim is:

1. In a slug casting machine, the combination of a composed line of matrices and expandable spacebands, a mold for casting a slug against the line, a pair of jaws between which the line is confined in casting relation to the mold, a justification bar movable in two stages to expand the spacebands in effecting respectively a preliminary and final justification of the line, means for operating the bar, and means for causing the bar in the first stage of its operation to engage the spacebands in an inclined position and then to be straightened out in effecting the preliminary justification of the line.

2. In a slug casting machine, the combination of a composed line of matrices and expandable spacebands, a mold for casting a slug against the line, a pair of jaws between which the line is confined in casting relation to the mold, a justification bar mounted so as to be capable of assuming a position inclined to and parallel with the matrix line and movable in two successive stages to expand the spacebands in effecting respectively a preliminary and final justification of the line, and means for operating the bar so as to cause it to assume first one and then the other of said positions during the first stage of its operation in effecting the preliminary justification of the line.

3. In a slug casting machine, the combination of a composed line of matrices and expandable spacebands, a mold for casting a slug against the line, a pair of jaws between which the line is confined in casting relation to the mold, a justification bar pivotally mounted and movable in two stages to expand the spacebands in effecting respectively a preliminary and final justification of the line, and means for operating the bar whereby the latter in the first stage of its operation is moved vertically while in an inclined position and then swung upwardly about its pivotal axis to a horizontal position in effecting the preliminary justification of the line.

4. In a slug casting machine, the combination of a composed line of matrices and ex-

5 pansible spacebands, a mold for casting a slug against the line, a pair of jaws between which the line is confined in casting relation to the mold, a spring-actuated justification bar mounted so as to be capable of assuming a position inclined to and parallel with the matrix line and movable in two successive stages to expand the spacebands in effecting respectively a preliminary and final justification of the line, and a cam for controlling the operation of the bar under the action of its actuating spring, the said bar being adapted during the first stage of its operation to assume first an inclined position and then a 10 horizontal position in effecting the preliminary justification of the line.

20 5. In a slug casting machine, the combination of a composed line of matrices and expansible spacebands, a mold for casting a slug against the line, a pair of jaws between which the line is confined in casting relation to the mold, a spring-actuated justification bar movable in two successive stages to expand the spacebands in effecting respectively a preliminary and final justification of the line, a pair of slide rods to which the bar is pivotally connected, and a pair of cams for controlling the operation of the bar through said rods, one of the cams being formed with 25 a recess for causing the bar to swing during the first stage of its operation from an inclined position to a horizontal position in effecting the preliminary justification of the line.

30 6. In a slug casting machine, the combination of a composed line of matrices and spacebands, a mold for casting a slug against the line, a movable jaw and a relatively fixed opposing jaw between which the line is confined in casting relation to the mold, a justification bar pivotally mounted so as to be capable of assuming a position inclined to and parallel with the matrix line and movable in two successive stages to expand the spacebands in effecting respectively a preliminary and final 35 justification of the line, means for causing the bar to assume first one and then the other of said positions in effecting the preliminary justification of the line, and means operated in synchronism with the bar for locking the movable jaw during both justifications of the line.

40 7. In a slug casting machine, the combination of a composed line of matrices and spacebands, a mold for casting a slug against the line, a movable jaw and a relatively fixed opposing jaw between which the line is confined in casting relation to the mold, a spring-actuated justification bar mounted so as to be capable of assuming a position inclined to and parallel with the matrix line and movable in two successive stages to expand the spacebands in effecting respectively a preliminary and final justification of the line, means for 45 causing the bar to assume first one and then

the other of said positions in effecting the preliminary justification of the line, a spring-actuated wedge movable into and out of action for locking the movable jaw in predetermined position during both justifications of the line, and unitary means for controlling the operation of the bar and wedge.

50 8. In a slug casting machine, the combination of a composed line of matrices and expansible spacebands, a mold for casting a slug against the line, a pair of jaws between which the line is confined in casting relation to the mold, a justification bar movable in two stages to expand the spacebands and effect respectively a preliminary and final justification of the line, a pair of springs for actuating said bar, and means for controlling the operation thereof whereby the bar is actuated by each of said springs successively in effecting the preliminary justification of the line.

55 9. In a slug casting machine, the combination of a composed line of matrices and expansible spacebands, a mold for casting a slug against the line, a pair of jaws between which the line is confined in casting relation to the mold, a justification bar pivotally mounted and movable in two stages to expand the spacebands and effect respectively a preliminary and final justification of the line, a pair of springs for actuating said bar, and means for controlling the operation of said springs whereby the bar during the first stage of its operation is moved bodily upward in an inclined position under the influence of one spring and then swung from the inclined position to a horizontal position under the influence of the other spring in effecting the preliminary justification of the line.

60 10. In a slug casting machine, the combination of a composed line of matrices and expansible spacebands, a mold for casting a slug against the line, a pair of jaws between which the line is confined in casting relation to the mold, a justification bar movable in two stages to expand the spacebands and effect respectively a preliminary and final justification of the line, a pair of springs for actuating said bar, and means for controlling the operation of said springs whereby the bar during the first stage of its operation is subjected to the influence of both springs in effecting the preliminary justification of the line.

65 11. In or for a linotype machine, the justifying cam O^1 formed with the relatively low portion O^3 , the intervening high portion O^6 , and the extended concentric portion O^6 , together with the depression O^7 located in the low portion O^3 , as and for the purpose described.

70 12. The method of justifying a composed line of matrices and spacebands in a linotype machine, which consists in subjecting the spacebands to the expanding influence of a movable bar operating in two successive

stages, and causing said bar in the first or preliminary stage to engage the spacebands while in an inclined position and then to move from its inclined position to a horizontal position to even up the spacebands.

⁵ In testimony whereof, this specification has been duly signed by.

EDWIN W. PIERSON.
